HYDRAULIC GOVERNOR COMPENSATION SYSTEM

Albert G. Massey, Watertown, N. Y., assignor, by mesne assignments, to Curtiss-Wright Corporation, New York, N. Y., a corporation of Delaware

Application September 27, 1955, Serial No. 536,932

4 Claims. (Cl. 121—42)

This invention relates to hydraulic governors for speed control and analogous uses.

The present invention relates generally to hydraulic governors of the type wherein the primary speed measuring element, a conventional flyball mechanism, connects directly with a pilot valve and, upon speed changes, moves the position of the latter, which in turn provides operating hydraulic fluid to an actuating piston and cylinder arrangement, the latter usually having connection with the control throttle of the prime mover, in cases where the hydraulic governor installation is serving to regulate the speed of such prime mover.

A practical hydraulic governor of the general type here under consideration must include compensating means in one form or another, such compensating means being provided to retard governor response and thereby avoid undue "hunting" during a correcting operation by the governor. The degree of compensation of governors of this general class varies according to requirements.

Where the compensating arrangement exerts a strong retarding influence the governor is naturally slower in its response to a speed change, that is to say, it is slower to produce an actual throttle change upon a speed change in the prime mover. In converse cases the compensation is termed "weak," that is there is a lesser retarding influence effected by the compensating arrangement and the governor, while quicker to respond to a given speed change, is more apt to produce "hunting" in the case of speed changes of considerable degree.

In the present invention a fluid pressure chamber is established which is compressed or expanded directly by movements of the pilot valve and by a compensating piston, both the pilot valve piston and the compensating piston communicating constantly with such fluid chamber. According to the present invention resilient push-pull means connect between the power piston and the compensating piston whereby movements of the former are not positively reproduced in the latter but are applied thereto in the form of resilient biasing forces.

Accordingly the compensating arrangement of the present invention comprises, in one piston and cylinder device, a basic compensating system and a combined accumulator and proportioning surge chamber arrangement. In the arrangement of the present invention the operating connection between the power piston and the resilient biasing means of the compensating piston is direct acting, the biasing means comprising a direct extension of the piston rod of the power piston, avoiding all mechanical linkages and other structural complications and then providing a simple and economical compensation and proportioning means.

The compensating system thus established comprises, under normal operating conditions, a closed fluid system save only for a leakage needle valve or similar adjustably reduced orifice which acts as a dashpot regulator directly upon the pilot valve in resistance to initial movement thereof.

Secondly, the needle valve acts as a bypass to propor-

2

tion the rate of time at which compensating fluid will act to close the pilot valve and thus proportions the degree of corrective movement of the power piston upon displacement of the pilot valve. Thirdly, the needle valve times the speed with which the pilot valve moves back to neutral in proportion to the speed of response of the engine so that the pilot valve will not move to open in the opposite direction under the pressure developed by the compensating piston.

10 In the general compensating arrangement of the present invention means are provided for acting in cooperation with the pilot valve fluid chamber and the compensating fluid chamber to provide a surge chamber both to serve as a pressure accumulator and to serve as a proportioning device to determine the degree of initial corrective movement to be made by the power piston in response to pilot valve displacement.

Various other aspects of novelty are referred to and pointed out in detail in the following detailed specification, taken in conjunction with the accompanying drawing. It is to be understood that the principles of the present invention are not limited to the precise forms set forth by way of example, but only as defined in the appended claims.

25 In the drawing:

Fig. 1 is a general schematic view of one form of the hydraulic governor of the present invention; and

Fig. 2 is a similar but fragmentary view of a portion of another form of the governor of the present invention.

30 In the form of governor illustrated by way of example in Fig. 1 of the drawing the numeral 10 designates a shaft connectible with the engine or other device or system to be governed. The purpose and effect of the governor system is to maintain a constant velocity of shaft 10 despite changes in load on the engine being governed or changes in other conditions which tend to vary the velocity of shaft 10 in other adaptations. Where the governor operates to maintain a constant velocity of shaft 10 despite differences in load on the apparatus being governed, for instance, the governor is said to be isochronous.

35 In the form of the invention now being described by way of example governing adjustment of the engine or other device or system being governed is accomplished by 40 rotating or oscillating a shaft designated 11 in the drawing, and, in the case of an engine, shaft 11 may be connected with the throttle valve or other fuel control means as by means of an arm 12. In the case of engine governing operation the load on the engine is reflected in the angular setting of shaft 11.

45 The flyweight head and the hydraulic fluid system which cooperates therewith operates in a housing 14 and comprises a shaft or sleeve 15 which rotates in a suitable bore in housing 14 and, in the present instance, is fixed directly to shaft 10 and may comprise an extension thereof, the shaft 10 being driven by the engine being governed.

50 Shaft 15 is bored to receive a pilot valve 16 which has axially spaced generally cylindrical valve heads 17 and 18 and is formed at its upper end with an enlargement 19. A pair of flyweights 20 are pivoted as at 21 to yoke formations 22 formed upon a flyweight yoke collar 23 which is fixed to shaft 15 in any desired manner. Flyweights 20 include finger portions 25 which bear upon a pin or bar 26 fixed to enlargement 19 of pilot valve 16, so that 55 outward pivotal movement of the flyweights 20 tends to move the pilot valve downwardly. An extension coil spring 30 is fixed at its lower end to enlargement 19 of pilot valve 16 and is supported at its upper end in a sleeve 31 which is carried by a casing 32.

60 Sleeve 31 is provided with internal means which support the upper end of extension coil spring 30 in such manner that the latter may be axially adjusted at its up-

per end to vary its resilient bias and the spring supporting means of sleeve 31 is also provided with anti-friction means whereby the upper end of the spring may rotate freely with pilot valve 16 while the sleeve 31 remains stationary. This spring supporting sleeve structure is known in the governor art and forms no part of the novelty of the present invention and accordingly need not be further illustrated or described herein.

From the foregoing it will be clear that any tendency of centrifugal force to move the flyweights outwardly, upon increase in speed of the shafts 10 and 15, tends to move the pilot valve 16 downwardly in the bore of shaft 15. A decrease in speed evidenced by a tendency of the flyweights to move inwardly toward the shaft 15 results in raising of the pilot valve under the impetus of coil spring 30. The pilot valve 16 rotates jointly with shaft 15 but is free to move axially therein as herein indicated.

The necessary hydraulic pressure required for operation of the governor is provided by a pump indicated at 35 which may be arranged to be driven from shaft 10 by a pair of gears 37 and 38. The pump 35 is preferably of the reversible type wherein the output is uni-directional regardless of the direction of rotation of the pump drive means. The outlet side of pump 35 communicates by means of a conduit 40, with an annular passage 41 formed in support 14 and extending about the shaft 15, whereby conduit 30 has continuous and uninterrupted communication with the space between valve heads 17 and 18 by way of a series of peripheral openings 42 in shaft 15.

The housing 14 has a pair of passages 47 and 48 and shaft 15 is provided with peripheral openings 49 and 50 which are normally axially in register with the valve heads 17 and 18 and also register axially with the passages 47 and 48 of housing 14, as illustrated in Fig. 1 of the drawing. The exterior periphery of shaft 15 at openings 49 and 50 is grooved as at 51 and 52 so as to maintain continuous communication between passages 49 and 50 and passages 47 and 48, respectively, during rotation of shaft 15.

Passages 47 and 48 communicate, respectively, with the upper and lower sides of a cylindrical chamber 53 formed in housing 14. A power or actuating piston 54 serves as a regulating member and is disposed in chamber 53 and has a piston rod 55 which connects pivotally with the outer end of an arm 56 fixed to shaft 11. In this way axial movement of piston 54 in chamber 53 directly produces rotative regulating movement of shaft 11 and thus the movements of piston 54 in chamber 53 directly determine and reflect the fuel setting of shaft 11, or any other variable condition which shaft 11 may serve to adjust.

Shaft 15 is formed with radial outlet passages 60 above upper valve head 17 and radial outlet passages 61 below lower valve head 18. The upper outlet passages 60 are in continuous communication with the general interior of casing 32 in which the governor is enclosed by way of an internal groove 64 in casing 14 and a passage 65 leading outwardly therefrom. The lower outlet passage 61 likewise communicates with an internal annular groove 67 formed in casing 14 and has free communication with the general interior of casing 32 by way of an outlet passage 68.

It will be seen from the foregoing that in a general way acceleration of shaft 10 will increase the centrifugal force on flyweights 20 and urge pilot valve 16 downward. The consequent lowering of valve head 18 connects pressure supply conduit 40 with conduit 48, thus directing fluid pressure against the lower side of piston 54. This corrective movement rotates shaft 11 in a counterclockwise direction to decrease the fuel setting, in instances where an engine is being governed, to accomplish the necessary slowing of shaft 10 to its desired speed level.

At the same time that conduit 48 is connected with

fluid pressure supply conduit 40, conduit 47 is connected with outlet passages 60 by reason of the lowering of valve head 17. This permits discharge of fluid from the space above piston 54 in chamber 53 through outlet passage 65.

The casing 32 which houses the governor mechanism itself comprises a reservoir or sump for pump 35 and all of the discharge outlets of the system discharge into the interior of casing 32 where they gravitate to the sump for reuse by the pump. In the form of governor illustrated herein the level of oil in casing 32 is maintained somewhat as indicated at 70 so that all passages which may take in fluid are submerged in the hydraulic medium.

Pilot valve 16 is further provided at its lower end with a piston head 71 which cooperates with the lower portion of the bore of shaft 15 to form a fluid pressure chamber 72.

Shaft 15 has one or more radial passages 79 terminating in a peripheral groove 80 which place the fluid pressure chamber 72 in continuous fluid communication with a passage 85 in housing 14. Passage 85 terminates in an adjustable restricted orifice by reason of a needle valve 90 which extends into passage 85 and is adjusted to more or less block the same by means of a threaded connection 91 in housing 14. It will be noted that the outer end of passage 85 is continuously submerged in the hydraulic medium 70.

Housing 14 is formed with a hollow cylindrical formation 95 which is disposed coaxially with power piston chamber 53 and is open at its lower end as at 96. Hollow cylindrical formation 95 forms a compensation piston chamber 98 which is in free fluid communication at its upper end with passage 85 as clearly shown in Fig. 1. A free floating compensating piston 99 is mounted in chamber 98 and, in effect, forms the lower end of the chamber 98 which is open to passage 85.

A pair of pre-compressed coil springs 101 and 102 bear, respectively, against the top and bottom of compensating piston 99. Lower spring 102 seats against the bottom of cylindrical formation 95 and the upper end of upper spring 101 bears against a spring seat or pressure pad 104 which is formed at the lower end of a rod 105 which comprises a downward extension, or tail rod on power piston 54.

The operation of the foregoing governor compensating and proportioning surge chamber structure will now be described, bearing in mind that the rudimentary governor operation involving merely the centrifugally controlled pilot valve and the throttle controlling power piston is conventional and has been described earlier herein. It will be noted that pilot piston chamber 72 and the space above compensating piston 99 in cylinder 95 are in free and continuous communication, and that the only external ingress or egress of fluid to the joint chamber thus formed is by way of the restricted orifice which is under the control of needle valve 90.

The piston 99 and its associated mechanism serve a twofold function as compensating means and as a proportioning surge chamber. If we ignore other influences for the moment, for ease and clarity of description, it will be noted that piston 99, being held between the balanced springs 101 and 102 will move up and down in response to up and down movements of the spring seat or pressure pad member 104, in direct proportion, each movement of pressure pad 104 being accompanied by a similar movement of piston 99 of one half the amount of the movement of pressure pad 104. The movements of pressure pad 104, in turn, occur directly by and with movements of the power piston 54.

If springs 101 and 102 were extremely stiff, so that they operated only to directly proportion the movement of compensating piston 99 to the movements of power piston 54, the compensating means thus provided would be particularly adapted to slow speed engines with heavy flywheels and proportionately slow response. The degree of governor response to a change in engine speed can be

reduced to any desired speed of correction by adjustment of the needle valve 90.

If the load on the engine being governed is reduced, its speed tends to increase and the consequent outward urge of flyweights 20 moves pilot valve 16 downward. This movement is resisted by the fluid under piston head 71 in chamber 72, its only mode of egress being past the restricted orifice in passage 85 formed by needle valve 90. In addition to this fluid resistance, downward movement of the pilot valve connects pressure from conduit 30 to the under side of power piston 54, causing upward movement of power piston 54 and pressure pad 104. This decreases the compression on spring 101 and the consequent excess pressure of spring 102 applies a resilient upward urge on compensating piston 99, tending to produce fluid flow from compensating piston chamber 98 into passage 85.

Again, because of the restriction interposed by needle valve 90, this movement tends to force fluid into chamber 72 and thus moves the pilot valve upward until movement of power piston 54 stops. The needle valve thus acts as a restrictive by-pass, and, depending upon its adjustment, the power piston 54 will move a degree sufficient to return the pilot valve 16 to neutral position.

At this point in the operation movement of the power piston and pilot valve are stopped but the engine, while approaching its initial speed because of the amount of adjustment imparted to rock shaft 11 by movement of power piston 54, has not gone down to initial speed. During this period the pilot valve is pushing down on the compensating fluid in chamber 72 with a force corresponding to the amount that the engine is off speed, and this force causes leakage past the needle valve while the engine is coming back to speed, the speed of such leakage being sufficient to prevent the pilot valve from moving away from neutral in the opposite direction.

If the throttle adjustment effected by the power piston 54 in the foregoing manner proves insufficient, the pilot valve again moves downwardly to further adjust the power piston, such further adjustment being of lesser degree than the first because the engine has partially returned to proper speed and the relative unbalance of the flyweight force is correspondingly less.

Upon an increase in load on the engine, a reverse governor operation takes place. The pilot valve 16 rises and power piston 54 moves downwardly. This tends to enlarge both the chamber 72 beneath pilot valve 16 and the compensating piston chamber 98. Thus, flow of fluid in passage 85 is from outside of housing 14 into the compensating piston chamber 98, the outlet end of passage 73 being submerged in hydraulic medium as heretofore described. The operation is otherwise the same in theory as upon reduction in load on the engine.

It will be noted from a study of the foregoing that the restricted orifice controlled by needle valve 90 serves a threefold function. First, it acts as a dashpot to regulate the initial pilot valve movement upon a deviation in speed of the engine being governed. Second, it serves as a by-pass to regulate the time period which will elapse before compensating fluid from compensating piston chamber 98 will raise the pilot valve 16 to neutral position and thus proportions the degree of governing movement of the power piston. Third, it serves as a time delay means during the period when the pilot valve is in neutral and motionless while the engine is responding to the completed adjustment of the power piston 54, preventing the pilot valve from opening in the opposite direction.

The system of Fig. 1 has thus far been described without considering the yieldability or energy-storing potentials of the springs 101 and 102 and, as described, is complete and operative for certain general purposes and to meet certain sets of operating conditions and factors. However, under certain conditions of use, the foregoing hydraulic governor system, without the energy-storing

capabilities of the springs 101 and 102, cannot be properly adjusted or proportioned to satisfactorily meet operating requirements.

The yieldable, energy-storing nature of the springs and the manner in which they modify the operation of compensating piston 99, constitute, in effect, refinements or additions to the general governor construction, arrangement and operation thus far described. These modifications in the operation of the foregoing basic governor arrangement extend the usefulness of the underlying system to applications and fields of usefulness for which the governor system without the compensating piston springs would be inadequate.

Compensating piston 99 will normally assume a neutral mid position in cylindrical formation 95, the pre-compressed springs 101 and 102 being of like characteristics. The push-pull action of the balanced force of the springs 101 and 102 on piston 99 causes the chamber 98 above the piston in cylindrical formation 95 to serve as an accumulator in either direction, positively or negatively, from the neutral position where the forces of springs 101 and 102 are in equilibrium.

This accumulator action is particularly well suited to modern high speed engines with quick response to throttle adjustment wherein there is less tendency for the governor to operate too fast and cause hunting. This accumulator action imparts greater flexibility of operation and the more yieldable nature of the forces imposed on the pilot valve by the compensating system gives the pilot valve more flexibility in producing control changes in the position of the power piston.

The embodiment illustrated fragmentarily in Fig. 2 comprises merely a modified arrangement of the compensating piston and its biasing springs and the manner in which those elements are related to the power piston tail rod. All of the other structure of the hydraulic governor of Fig. 2 is the same as that shown and described in connection with Fig. 1 and need not be further illustrated and described.

In Fig. 2 a sleeve or skirt formation 110 extends downwardly from housing 14 to form a hollow cylindrical extension coaxial with the power piston chamber 53. A free compensating piston 111 is mounted in this cylindrical extension and a tail rod 112 extends downwardly from power piston 54 and through compensating piston 111 in free axial sliding relation to the latter.

A pair of compression coil springs 114 and 115 bear respectively against the top and bottom of compensating piston 111, the upper end of upper spring 114 seating against a collar 117 fixed to tail rod 112 and the lower end of lower spring 115 seating against a collar or washer 118 which is removably held in place at the lower end of tail rod 112 by a nut 120.

The compression coil springs 114 and 115 are pre-compressed as in the preceding example and the functional operation of the embodiment of Fig. 2 is precisely the same as that previously described in connection with Fig. 1. The main distinction of the embodiment of Fig. 2 as compared with the embodiment of Fig. 1 reside in the fact that the piston 111 of Fig. 2 and the tail rod 112 serve as mutual guides to maintain coaxial alignment of these parts and the open construction of the bottom of cylindrical sleeve 110 permits ready removal of the compensating piston and its compression coil springs for replacement or repair.

The compensating piston elements 99 and 111 may comprise diaphragm or any equivalent expansible chamber members and, instead of the balanced compensation piston springs described above, a single normally neutral or unstressed compression-extension coil spring of the push-pull type may be used in conjunction with either of the compensating pistons or their equivalent expansible chamber members.

What is claimed is:

1. A hydraulic governor comprising a hydraulic pres-

sure regulator cylinder and a piston movable therein, a source of operating fluid pressure therefor, a pilot valve movable in opposite directions to connect said fluid pressure source to move said regulator piston in opposite directions, a fluid pressure chamber and a piston movable directly with said pilot valve for compressing and expanding said chamber upon movement of the pilot valve in opposite directions, a compensating cylinder coaxial with said regulator cylinder and a piston therein movable to compress and expand said compensating cylinder chamber, said two chambers being in continuous fluid communication, an adjustable leakage orifice leading from the fluid system comprising said two chambers to a source of fluid under substantially no pressure, normally balanced opposed springs acting against opposite sides of said compensating piston for yieldably tending to retain the same in a neutral position, a connecting rod extending from said regulator piston into said compensating cylinder and having means acting against one of said springs to vary the neutral position of said compensating piston upon movement of said regulator piston.

2. A hydraulic governor comprising a hydraulic pressure regulator cylinder and a piston movable therein, a source of operating fluid pressure therefor, a pilot valve movable in opposite directions to connect said fluid pressure source to move said regulator piston in opposite directions, a fluid pressure chamber and a piston movable directly with said pilot valve for compressing and expanding said chamber upon movement of the pilot valve in opposite directions, a compensating cylinder coaxial with said regulator cylinder and a piston therein movable to compress and expand said compensating cylinder chamber, said two chambers being in continuous fluid communication, normally balanced opposed springs acting against opposite sides of said compensating piston for yieldably tending to retain the same in a neutral position, a connecting rod extending from said regulator piston into said compensating cylinder and having means acting against one of said springs to vary the neutral position of said compensating piston upon movement of said regular piston.

3. A hydraulic governor comprising a hydraulic pressure regulator cylinder and a piston movable therein, a source of operating fluid pressure therefor, a pilot valve movable in opposite directions to connect said fluid pressure source to move said regulator piston in opposite directions, a fluid pressure chamber and a piston movable directly with said pilot valve for compressing and expanding said chamber upon movement of the pilot valve in opposite directions, a compensating cylinder coaxial

5 with said regulator cylinder and a piston therein movable to compress and expand said compensating cylinder chamber, said two chambers being in continuous fluid communication, an adjustable leakage orifice leading from the fluid system comprising said two chambers to a source of fluid under substantially no pressure, normally balanced opposed springs acting against opposite sides of said compensating piston for yieldably tending to retain the same in a neutral position, a connecting rod extending from said 10 regulator piston into said compensating cylinder and having means acting against one of said springs to vary the neutral position of said compensating piston upon movement of said regulator piston, said connecting rod means acting on said one of said springs to yieldably compress said compensating cylinder chamber upon compressing movement of said pilot valve piston and yieldably expand the same upon expanding movement of the pilot valve piston.

20 4. A hydraulic governor comprising a hydraulic pressure regulator cylinder and a piston movable therein, a source of operating fluid pressure therefor, a pilot valve movable in opposite directions to connect said fluid pressure source to move said regulator piston in opposite directions, a fluid pressure chamber and a piston movable directly with said pilot valve for compressing and expanding said chamber upon movement of the pilot valve in opposite directions, a compensating cylinder coaxial with said regulator cylinder and a piston therein movable to compress and expand said compensating cylinder chamber, said two chambers being in continuous fluid communication, normally balanced opposed springs acting against opposite sides of said compensating piston for yieldably tending to retain the same in a neutral position, a connecting rod extending from said regulator piston 25 into said compensating cylinder and having means acting against one of said springs to vary the neutral position of said compensating piston upon movement of said regulator piston, said connecting rod means acting on said one of said springs to yieldably compress said compensating cylinder chamber upon compressing movement of said pilot valve piston and yieldably expand the same upon expanding movement of the pilot valve piston.
